UNITED STATES PATENT OFFICE.

RICHARD MACHENBACH, OF BERLIN, GERMANY, ASSIGNOR TO THE FIRM OF SPRENGSTOFF A.-G. CARBONIT, OF HAMBURG, GERMANY.

RIFLE SHELL OR GRENADE WITH PERCUSSION-FUSEE.

1,094,340.

Specification of Letters Patent. Patented Apr. 21, 1914.

Application filed December 19, 1913. Serial No. 807,683.

To all whom it may concern:

Be it known that I, RICHARD MACHENBACH, a subject of the German Emperor, and resident of Berlin, Germany, have invented 5 a certain new and useful Rifle Shell or Grenade with Percussion-Fusee, of which the following is a specification.

The present invention relates to rifle-shells or grenades having a larger diameter than 10 the rifle or other similar arm or gun firing the same. More particularly the said invention includes a locking device for the percussion bolt, which is released by the oscillation or movement of a lever or other part 15 of the grenade when the latter is stuck on to the barrel.

In the present grenade the oscillating lever or movable part does not act directly on the percussion bolt or striker to hold the 20 same, but acts first on a fan, which after being released does not release the percussion bolt until the projectile has moved a certain distance on its trajectory. The employment of a fan for setting grenades at firing position 25 is known *per se*, however these known fans act as independent locking means or they must be unbolted or released by hand before firing the grenade by removing a cap or a pin. According to the present invention 30 the fan is released by the action of attaching the grenade on the barrel of the rifle or gun and the fan then releases the percussion bolt automatically after the lapse of a certain space of time.

35 The present invention prevents an untimely bursting of the shell or grenade. It may happen, that in firing grenades such as spoken of in the preamble of this description, the percussion bolt or striker rebounds 40 or is launched forward by repulsion and thereby hits with its percussion cap or primer against the needle, thus causing an untimely bursting. This danger is removed by introducing a screw fan between the releasing lever and the locking bolt, by which 45 means the fusee will not be in a firing position before the projectile has moved 50 to 200 meters from the muzzle of the barrel according to need. The invention therefore 50 combines the advantages of a time-fuse with a releasing device which automatically and positively operates independently from the position of the grenade, when stuck on to the barrel of the gun.

55 In the accompanying drawing Figure 1 is

a longitudinal section of grenade embodying one form of my invention, and Fig. 2 is a like view of another form.

The fuse consists of a shaft 5 having the known form of tube 6, the percussion bolt 7 carrying a percussion pellet 8 adapted to reciprocate within the tube 6, the needle 9 together with the detonator 10 and safety spring 11. A catch comprising a two armed lever 17 (Fig. 2) projects into the bore 12 of the shaft 5 and is connected at its outer projecting end with a pin or spline 15, which engages a safety ring or fan 18 to prevent it from rotating. This fan is provided within its boss with a female thread and is screwed 70 on a corresponding male thread of the fuse shaft 5 in such way that it normally holds a retaining pin 14 against the action of the spring 16 in its bore which pin holds the percussion bolt 7 in its retracted position. The 75 spline 15 projects (similar to a shaft-key) half in a notch of the fuse shaft 5 and half in a notch of the boss of the fan 18.

The operation of the device is as follows: 80 When the grenade is placed on the barrel of the gun and the outer end contacts with the lever 17, the latter is oscillated and thus withdraws the spline 15 from the notch of the fan 18, so as to allow the fan to rotate on the screw thread. After firing, the fan 18 85 is rotated on the threaded part of the shaft, by the action of the air, and liberates the retaining pin 14, which is thrown out by the spring 16. By making the thread longer or shorter, the moment, in which the fuse is set 90 in firing position, may take place according to need 50 to 200 meters in front of the muzzle of the gun. The lever 17 and the spline 15 are so dimensioned that the lever 95 can oscillate to such extent that the safety ring together with the vanes can slide past the lever and may fall over the guide bar of the projectile so as not to retard the projectile in its further flight.

In the form shown in Fig. 1 I have substituted a slideable pin for the lever 17. This pin 17' is mounted in a longitudinal bore of the shaft 5 and has a laterally projecting tongue 15' which engages a notch in the upper end of the boss of the fan 18, so as to prevent the automatic rotation of the fan. The lower end of the pin 17' projects into the bore 12 of the shaft 5, when the tongue 15' is in engagement with the boss of the fan. This pin is projected forward by slid- 100 105 110

ing the grenade on the barrel of the gun and thus the tongue 15' releases the fan 18 and may be itself thrown out by a small spring similar to spring 16 but not shown. After 5 firing the projectile the fan rotates on account of the friction of the air, and is screwed backward on the threaded part of the shaft 5, thus also releasing the locking pin 14 which is then thrown out by 10 the action of the spring 16. Thus the fusee is set at firing position automatically at a variable distance.

I claim:

1. A grenade of the character described, 15 comprising a percussion bolt, a retaining member therefor, a safety member to hold the retaining member in position, means on the safety member to rotate the latter, during the flight of the projectile, to release the 20 retaining member, and a catch to normally

lock the safety member against rotation, said catch being automatically operated to release the safety member by positioning the grenade on the gun barrel.

2. A grenade of the character described, 25 comprising a tube, a percussion bolt movable therein, a pin to hold the bolt in a retracted position, a spring to retract the pin, a safety ring on the tube and normally inclosing the pin, vanes on the ring to rotate the latter 30 during the flight of the grenade to move the ring longitudinally of the tube, and means to normally lock the ring against rotation, said locking means being automatically operable to release the ring by positioning the 35 grenade on a gun barrel.

RICHARD MACHENBACH.
